(57) **CLAIM**

The ornamental design for a tie for composite wall, as shown and described.

DESCRIPTION

FIG. 1 is a perspective view of an ornamental design for a tie for composite wall according to the present invention; FIG. 2 is a top view of the tie for composite wall of FIG. 1; FIG. 3 is an opposite bottom view of the tie for composite wall of FIG. 1;

FIG. 4 is a first side view of the tie for composite wall of FIG. 1;

FIG. 5 is an opposite second side view of the tie for composite wall of FIG. 1;

FIG. 6 is a front end view of the tie for composite wall of FIG. 1; and,

FIG. 7 is an opposite rear end view of the tie for composite wall of FIG. 1.

The broken lines in the drawings illustrate portions of the tie for composite wall which form no part of the claimed design.
